UNITED STATES PATENT OFFICE.

CARL BLECHER, OF BERLIN-DAHLEM, GERMANY, ASSIGNOR TO ROTOPHOT AKTIEN-
GESELLSCHAFT FÜR GRAPHISCHE INDUSTRIE, OF BERLIN, GERMANY.

PROCESS OF PRODUCING COMBINATION PRINTING-PLATES FOR PRINTING COMBINED
HALF-TONE AND PRINTED TYPE OR LINE WORK.

1,150,414.

Specification of Letters Patent. Patented Aug. 17, 1915.

No Drawing.

Application filed January 27, 1915. Serial No. 4,786.

To all whom it may concern:

Be it known that I, CARL BLECHER, subject of the King of Prussia, residing at Berlin-Dahlem, Germany, Friedbergstrasse 23, have invented certain new and useful Improvements in the Process of Producing Combination Printing-Plates for Printing Combined Half-Tone and Printed Type or Line Work, of which the following is a specification.

My invention relates to the production of printing plates for printing photo-engravings on the printing press, and more especially to a method for making the diapositives used for this production. In the art of making combined half-tone and printed type and line-work printing plates a diapositive showing the printed type and line-work between the pictures is employed, this diapositive being printed on etching paper; the print is then transferred onto the printing plate, developed and dried. Thereupon first of all the places carrying the printed type and line work are protected with varnish and the pictures are etched. The varnish is then removed, the pictures are protected in their turn against the attack from the etching liquid and the printed type and line work is etched, whereupon the varnish and print are removed from the plate which is now ready for printing on the press.

Owing to the repeated protecting and etching operations required the method described is exceedingly tiresome and therefore expensive. It has been, however, unavoidable, the practice having shown that the time used for etching the printed type and line work must be less in all cases than the time for etching the pictures. If one were to etch both the line work and the picture for an equal length of time, in case that the line work came out right, the pictures would appear too weak, while, if the time was right for the pictures, then the line work would come out too strongly and would appear too broad.

According to my invention, in order to avoid etching the printed type or line work and the pictures separately, the degree of translucency of the printed type or line work elements on the one hand and of the darker shades of the pictures on the other hand, which had never heretofore been taken into account, is determined in such a

way that the printed type and line work are less covered (in the photographic sense), than the darker and the darkest parts of the pictures. This method renders it possible to produce, on the printing plate, prints of the line work or printed type and of the pictures which can be etched simultaneously, the etching of the printed type and line work elements starting later than the darker and darkest shades of the pictures, in strict accordance with the greater height of the line work relief resulting from the greater translucency of the lines in the diapositive, as compared with the height of the relief of the dark parts of the pictures, which owing to their lower translucency is considerably less. It is a matter of experience to determine the appropriate difference of translucency of the different kinds of reproduction and it is impossible to lay down definite rules of general value regarding the absolute degree of covering of the printed type or line work and the pictures, this depending to a great extent upon the peculiarities of the printing (copying) method employed in each case. However there is no need for the colors of the line work and pictures to agree, provided that the covering of the line work elements and the darker and darkest shades of the pictures is tuned so as to make the former less than the latter.

In practising my invention I may proceed for instance as follows: The printed type or line work is printed in blue, that is to say, in a color allowing a great amount of actinic light to pass through, upon a collodion or celluloid film or the like. This print is then placed with the type or lines downward upon the picture diapositive, care being taken that the printed type and line work are in the right places between the pictures. The film is then fixed upon the diapositive and printed. In the copy taken on the printing plate the relief of the printed type and line work will appear higher than the relief of the darkest parts of the picture.

If the hydrotype process is used for transferring the printed type and line work onto the plate, the concentration of the coloring bath or the time of acting upon the print need only be chosen low enough to insure such a weak coloring of the lines. The same applies to the other methods of translation: in some cases the application of a suitable

difference between the times of exposure for the different kinds of reproduction will suffice to produce the desired effect.

I claim:—

- 5 1. The herein-described improvement in the method of producing combination printing plates of the character described, comprising producing a translucent reproduction of the subject having picture and type impression
- 10 portions, in which reproduction type impression portions are less dense than the darkest part of the picture portion, and producing on a printing plate a print from said reproduction.
- 15 2. The herein-described improvement in the method of preparing a plate for printing

combined half tone and type or line work, comprising providing a diapositive of the picture to be reproduced, combining therewith a photographic reproduction of the ²⁰ type or line work that is more translucent than the portions of the diapositive representing the dark parts of the picture, and producing a print of said diapositive and photographic reproduction on a printing ²⁵ plate.

In testimony whereof I affix my signature in presence of two witnesses.

CARL BLECHER.

Witnesses:

WILLY P. H. MARTIN,
HENRY HASPER.
